UNITED STATES PATENT OFFICE.

GEORGE MANIERRE, OF MILWAUKEE, WISCONSIN.

HEATING DEVICE.

Application filed December 19, 1924. Serial No. 756,942.

This invention relates to a heating device, and particularly to a device for preventing the freezing of the cooling fluid of combustion engines while the engines are being kept at rest in very cold weather. It occurs very frequently that the water in the radiator and radiator conduits of automobiles freezes when the automobile is left standing in the garage for over-night or for several days without being used.

The present invention has the object of overcoming this disadvantage by introducing into the conduit which may lead from the radiator a small heater adapted to be connected with the source of heat accessible from the dashboard or some other readily accessible part of the machine.

It is also an object of the invention to provide a heater which will facilitate the starting of the engine in cold weather and for this purpose to introduce the heater into the cooling system of the engine so as to heat the water from which the heat will be transmitted to the engine oil.

It is another object of the invention to facilitate this mounting or dismounting of the heating device by providing it with a casing which readily can be inserted into the conduit of the radiator and which will be kept fluid-tight without requiring any parts to be welded together or without occupying excessive additional space under the hood of the engine.

It is, furthermore, an object of the invention to provide a heating device of this character in which the casing parts are identical and can readily be assembled to form a fluid-tight casing having an inlet and outlet opening only for the support of those means through which the heat is supplied to the heating device of the interior of the casing.

With these and numerous other objects in view an embodiment of the invention has been illustrated in the accompanying drawings wherein

Fig. 1 is a side elevation of a portion of an automobile showing the device in place, certain of the parts being shown broken away;

Fig. 2 shows on a larger scale a central, longitudinal section through the casing with the heating device therein in elevation;

Fig. 3 is a transverse, sectional view on line 3—3 of Fig. 2, and

Fig. 4 shows one of the casing parts perspective.

The radiator 1 which is conventionally shown in Fig. 1 as being located near the front part of an automobile engine, communicates through the conduits 2 and 3 with a water circulating device which is not illustrated in the drawings. The invention is adapted to be applied to one of these conduits, as for instance to the hose leading from the lower end of the radiator to the pipe which extends to the pump, not shown. This hose is severed by a transverse cut, and the casing 4 having reduced ends 5 is inserted into the adjacent severed portions of the hose and held securely therein by means of clamps 6 of any desired construction.

The casing 4 preferably is composed of two substantially cylindrical portions 7 integral with the attachment extensions or reductions 5. A relatively large part 8 of the margin of each cylindrical portion 7 is located in a plane at right angles to the axis of the portion 7. In order to facilitate the attachment of this part to the companion part of identical construction the margin is provided with a reinforcing flange 9 extending over the entire length of said margin. This edge is provided with an angular projection 10 extending from the portion 8 axially outward of said plane, and is provided furthermore with an indentation 11 extending from the portion 8 axially inward, said indentation 11, however, being deeper than the projection 10.

In the assembly of the companion parts of which the casing is formed these parts are placed in axial alinement and rotated relatively to each other until the indentation or notch 11 of the edge in one part is in opposition to the projection 10 of the other part, and vice versa. The height and depth respectively of these projections and indentations is made so large that upon the assembly of the parts as stated, there remains between the deepest portion of the indentation and the highest portion of the abutting projection a circular opening 13 permitting the passage of a small hose or tubing 14 through the wall of the casing. This tubing of circular cross-section preferably contains a wire 15 of a material to be heated when connected with the ordinary commercial source of electricity, as for instance, a lampsocket for illuminating purposes. The heating ele-

ment consisting of the wire 15 is preferably wound in the form of a helix with about two turns so that the two ends of this heating wire 15 project thru the same side of the 5 casing. At the projecting ends the terminals of conductors 16 are secured to the ends of the wire 15, the conductors leading to a socket 17 preferably arranged on the dashboard 18 and adapted to receive the ordinary 10 light plug, not shown in the drawing.

The entire structure comprising the assembled casing with the heating element securely held therein may be sold as an article of manufacture and may readily be inserted 15 into the tube connection extending from the radiator without interfering with the water circulation. The attachment can be put in place without requiring skilled help. After the parts have been assembled to form the 20 casing—the joint of the two casing parts is improved by pouring a fluidtight element or the like—into the circumferential groove 20 formed in the assembled casing at the abutting ends of the parts since these parts are 25 provided at their outer circumference with a bevelled edge 21.

It has already been proposed to place an electric heater in the interior of the engine hood to heat the entire interior by radiation. 30 An excessive amount of heat is required and the costs of operation, therefore, are exorbitant. In the present case heat is produced in the interior of the conduit only, the water

cooling system then acts as a water heating system and the engine oil receives its heat 35 through the walls of the cylindrical base. Owing to the reduction of the heat required by this method the costs of operation also are correspondingly reduced.

Owing to the insertion of the electric heater into the water conduit itself, the water will be gradually heated upon energization 40 of the heater and in cold weather this is of great advantage, as thereby the entire engine will be brought to a temperature at which 45 the starting is facilitated.

I claim:

As an article of manufacture, a casing composed of two identical parts and firmly joined together, the casing being adapted in 50 assembled form for insertion into the radiator conduit of an automobile, each casing part having a cylindrical portion terminating in a margin which is provided with a projection and an indentation, a resistance 55 coil inserted in said casing and supported insulated from the same, the projection on each casing part being of less height, measured axially, than the depth of the indentation on the other casing part to leave a space 60 between the interfitted indentations and projections, the ends of the resistance coil being insulatingly supported in said space.

In testimony whereof I affix my signature at 114 Grand Ave., Milwaukee, Wisconsin.

GEORGE MANIERRE.
